No. 836,449

PATENTED NOV. 20, 1906.

C. A. LEWALLEN & L. E. STETLER.

SMOKE CONSUMER.

APPLICATION FILED NOV. 11, 1905.

UNITED STATES PATENT OFFICE.

CHARLES A. LEWALLEN, OF KANSAS CITY, KANSAS, AND LEWIS E. STETLER, OF MINNEAPOLIS, MINNESOTA, ASSIGNEES OF ONE-THIRD TO GEORGE L. MATCHAN, OF MINNEAPOLIS, MINNESOTA.

SMOKE-CONSUMER.

No. 836,440.

Specification of Letters Patent.

Patented Nov. 20, 1906.

Application filed November 11, 1905. Serial No. 286,825.

To all whom it may concern:

Be it known that we, CHARLES A. LEWALLEN, residing at Kansas City, in the county of Wyandotte, State of Kansas, and Lewis E. STETLER, residing at Minneapolis, in the county of Hennepin, State of Minnesota, citizens of the United States, have invented certain new and useful improvements in Smoke-Consumers; and we do hereby declare the following to be a full, clear, and exact description of the invention, such as will enable others skilled in the art to which it appertains to make and use the same.

Our invention relates to steam-generating boilers, and has for its object to provide an improved means for effecting complete combustion of the fuel, thereby preventing the discharge of smoke and resulting in economy in the use of fuel.

20 To the above ends the invention consists of the novel devices and combinations of devices hereinafter described, and defined in the claim.

25 The invention is illustrated in the single view of the drawing, which is a vertical section taken centrally and longitudinally through a boiler and our improved attachment, some parts being broken away.

30 The numeral 1 indicates the fire-box, the numeral 2 the boiler proper, the numeral 3 the flues, the numeral 4 the smoke-box, and the numeral 5 the smoke-stack of a steam-generating plant of standard construction.

35 In the application of our invention to this boiler we employ a cylinder 6, rigidly supported by any suitable means, as by legs 7. A piston 8 works within the cylinder 6, and its stem 9 works outward through one head thereof and, as shown, is connected by a rod 40 to a power-driven crank-arm 11, a portion only of which is shown.

45 A smoke-return flue 12 leads downward from the smoke-stack 5 and is provided with branches 12^a and 12^b, that open, respectively, into the left-hand and right-hand ends of the cylinder 6. Check-valves 13 normally close the lower extremities of the branch flues 12^a and 12^b and permit the flow of air into the cylinder, but prevent an outward flow through the respective branch flues. Check-valves 50 14 open from the atmosphere into the branch flues 12^a and 12^b. These air-valves 14 are normally closed and open up and admit more

or less fresh air under each suction-stroke of the piston.

55 Branch outlet-flues 15^a and 15^b open from the left-hand and right-hand ends, respectively, of the cylinder 6 and lead to a common return-flue 15, which in turn extends into the fire-box 1, above the grates thereof. 60 Check-valves 16 normally close the branch flues 15^a and 15^b, but readily open up under pressure thereon from within the cylinder 6.

65 The return-flue 12 is preferably formed in two sections that are connected by a closed precipitating chamber or vessel 17 (shown as rigidly secured by a bracket 17^a) to the smoke-box 4. The section of the flue 12 which leads directly from the smoke-stack 5 terminates near the bottom of the precipitating-chamber 17, and the other section of said flue 12 leads downward from the upper portion of said chamber. Between the separated ends of the two sections of the flue 12 is a screen 18, that preferably extends entirely across the precipitating-chamber 17. The numeral 19 indicates a downwardly-closed hand-hole in one side near the bottom of the precipitating-chamber 17.

70 The operation of the attachment is substantially as follows: By continuous rotation of the crank 11 the piston is reciprocated first in one direction and then in the other. Under movement of the piston from the left toward the right a greater part of the escaping parts of combustion from the smoke-box 4, including the smoke, will be drawn through the flue 12 12^a into the left-hand end of the cylinder 6, and any smoke, hot air, or other products of combustion in the right-hand 75 end of the cylinder will be forced through the flue 15 15^b into the fire-box directly on the burning fuel. Under a movement of the piston 8 from the right toward the left the products of combustion from the smoke-box 4 may 80

85 be drawn through the lead-flue 12 12^b into the right-hand end of the cylinder 6, while the products of combustion previously drawn into the left-hand end of the cylinder will be forced through the flue 15 15^a back into the 90 fire-box. As the smoke and the products of combustion pass from the lower end of the first flue-section 12 soot and other solid particles will be precipitated to the bottom of the chamber 17 and cannot of course pass 95 through the screen 18. Hence the smoke is 100

relieved of the soot, and the precipitated soot may be collected from time to time and removed at the hand-hole 19. This soot has a commercial value, and for that reason alone it is desirable to collect the same. If desired, sufficient water may be forced in the bottom of the precipitating-chamber 17 to cover the depending end of the first flue-section 12, and in this case the screen 18 might be dispensed with. Under the reverse reciprocations of the piston 8 a continuous circulation of the smoke and other products of combustion is kept up from the smoke-box through the precipitating-chamber 17, cylinder 6, and back into the fire-box, and all combustible particles are either completely burned or precipitated into the chamber 16. This device is therefore in the nature of a smoke-consumer as well as a fuel-saving device.

The improved device or attachment may of course be applied to boilers of any and all kinds. In the drawing the attachment is shown as located directly in front of the fire-box of the boiler; but it will of course be understood that in practice it may be located where found most convenient or desirable. From what has been said it will be understood that the cylinder 6 and piston 8 afford a double-acting cylinder-and-piston pump

for producing the forced circulation of the returned products of combustion.

What we claim is—

The combination with a boiler, of a cylinder-and-piston pump 6-8, and means for reciprocating the piston 8 thereof, of a flue 12 leading from the smoke-outlet of said boiler, and having branches 12^a and 12^b opening into the opposite ends of said cylinder, check-valves 13 coöperating with the inner extremities of said flues 12^a and 12^b, fresh-air check-valves 14 opening into said branch flues 12^a and 12^b, branch flues 15^a and 15^b leading from the opposite ends of said cylinder and joining in a single flue 15 that opens into the fire-box of said boiler, and check-valves 16 coöperating with the inner extremities of said branch flues 15^a and 15^b, substantially as described.

In testimony whereof we affix our signatures in the presence of two witnesses.
